UNITED STATES PATENT OFFICE.

MILTON D. MENDLE, OF ST. LOUIS, MISSOURI, ASSIGNOR TO AMERICAN FIXTURE & SHOWCASE MANUFACTURING COMPANY, OF ST. LOUIS, MISSOURI, A CORPORATION OF MISSOURI.

DESIGN FOR A DISPLAY-RACK BASE.

Application filed December 12, 1928. Serial No. 29,238. Term of patent 3½ years.

To all whom it may concern:

Be it known that I, MILTON D. MENDLE, a citizen of the United States, residing in the city of St. Louis, State of Missouri, have invented a certain new, original, and ornamental Design for a Display-Rack Base, of which the following is a specification, reference being had to the accompanying drawing, forming a part thereof, and in which—

Figure 1 illustrates in plan and Figure 2 illustrates in side elevation a display-rack base embodying my new design.

I claim—

The ornamental design for a display-rack base substantially as shown.

MILTON D. MENDLE.
